Fig. 5

Fig. 2

Fig. 3

FIG. 1 is an isometric view of a cabinet showing my new design;

FIG. 2 is a front elevational view thereof;

FIG. 3 is a side elevational view thereof;

FIG. 4 is a top plan view thereof;

FIG. 5 is a bottom plan view thereof; and

FIG. 6 is an enlarged partial detail view of the portion encircled by the lines 6—6 of FIG. 1.

Both sides of the cabinet are identical.

The dominant characteristics of my design reside in the specific drawer pulls in conjunction with the inset corner features of the cabinet front face, which features are best illustrated in FIG. 6.

I claim:

The ornamental design for a cabinet, as shown and described.
